[57] CLAIM

The ornamental design for a combined housing and removable cap of a sample analyzer, as shown and described.

DESCRIPTION

FIG. 1 is a front, top, side perspective view of a combined housing and removable cap of a sample analyzer, with the cap attached;

FIG. 2 is a front, top, side perspective view thereof, with the cap removed;

FIG. 3 is a top plan view thereof, with the cap attached;

FIG. 4 is a bottom plan view thereof;

FIG. 5 is a side elevational view thereof;

FIG. 6 is a side elevational view thereof, opposite that shown in FIG. 5;

FIG. 7 is a front end elevational view thereof, showing the cap; and,

FIG. 8 is a rear end elevational view thereof, showing the housing.

The broken line showing in FIGS. 1-3 is for illustrative purposes only and forms no part of the claimed design.
